US0D1020851S

(12) **United States Design Patent** (10) **Patent No.:** **US D1,020,851 S**
(45) **Date of Patent:** **** Apr. 2, 2024**

(54) **SMARTGLASSES**

(71) Applicant: **Innovative Eyewear, Inc.**, North Miami, FL (US)

(72) Inventors: **David Cohen**, Aventura, FL (US); **Harrison Gross**, North Miami, FL (US); **Breno Fuzette**, Santa Terezinha (BR); **Matthew Gale**, Brooklyn, NY (US)

(73) Assignee: **Innovative Eyewear, Inc.**, North Miami, FL (US)

(**) Term: **15 Years**

(21) Appl. No.: **29/870,959**

(22) Filed: **Feb. 9, 2023**

(51) LOC (14) Cl. **16-06**

(52) U.S. Cl.

USPC **D16/309**

(58) **Field of Classification Search**

USPC D16/300, 309, 329, 330, 336; D21/483, D21/659-661; D14/372

CLAIM

The ornamental design for smartglasses, as shown and described.

DESCRIPTION

FIG. 1 is a front top perspective view of smartglasses showing our new design;

FIG. 2 is a rear bottom view thereof;

FIG. 3 is a front view thereof;

FIG. 4 is a rear view thereof;

FIG. 5 is a top view thereof;

FIG. 6 is a bottom view thereof; and,

FIG. 7 is a left side view thereof, which is a mirror image of a right side view thereof.

The broken lines in the drawings are for the purpose of illustrating unclaimed portions of the smartglasses and form no part of the claimed design.

1 Claim, 4 Drawing Sheets
